(57) **CLAIM**

An ornamental design for a bicycle freehub component as shown and described.

DESCRIPTION

FIG. 1 is a bottom perspective view of a first embodiment of a bicycle freehub component;

FIG. 2 is a top perspective view thereof;

FIG. 3 is a left side view thereof;

FIG. 4 is a right side view thereof;

FIG. 5 is a bottom view thereof;

FIG. 6 is a top view thereof;

FIG. 7 is a front view thereof;

FIG. 8 is a back view thereof;

FIG. 9 is a bottom perspective view of a second embodiment of a bicycle freehub component;

FIG. 10 is a top perspective view thereof;

FIG. 11 is a left side view thereof;

FIG. 12 is a right side view thereof;

FIG. 13 is a bottom view thereof;

FIG. 14 is a top view thereof;

FIG. 15 is a front view thereof;

FIG. 16 is a back view thereof;

FIG. 17 is a bottom perspective view of a third embodiment of a bicycle freehub component;

FIG. 18 is a top perspective view thereof;

FIG. 19 is a left side view thereof;

FIG. 20 is a right side view thereof;

FIG. 21 is a bottom view thereof;

FIG. 22 is a top view thereof;

FIG. 23 is a front view thereof; and,

FIG. 24 is a back view thereof.

The broken lines illustrate portions of the bicycle freehub component that form no part of the claimed design.

1 Claim, 24 Drawing Sheets
